ATTORNEY.

UNITED STATES PATENT OFFICE.

HARVEY HADDEN, OF PEEKSKILL, NEW YORK.

EAR-MUFF.

SPECIFICATION forming part of Letters Patent No. 479,185, dated July 19, 1892.

Application filed December 18, 1889. Serial No. 334,241. (No model.)

To all whom it may concern:

Be it known that I, HARVEY HADDEN, a citizen of the United States, residing in the village of Peekskill, in the county of West-
5 chester and State of New York, have invented a new and useful Ear-Muffler, of which the following is a specification.

My invention relates to coverings for the ear, and has for its object the attachment to
10 a hat or cap of a muff that may be easily and quickly caused to cover the ear and instantaneously be made to fold within the hat. These objects are attained by the means set forth in the accompanying drawings, in
15 which—

Figure I represents a muff complete. Fig. II represents a hat in cross-section, showing the operation of the muff. Fig. III shows how the muff is attached to the rim of a hat.
20 In construction a metallic piece *a*, having the round stem *b* and the flattened ends *c c*, bent at right angles to the said stem, constitutes the hanger for the muff. A wire loop
25 *d*, having its ends bent into spirals *e e*, is covered with the muff fabric *f*, and the spirals are slipped on the stem *b*, with their ends fastened to the stem, as shown at *g*, the wire having a spring-temper. The spirals of course tend to hold the muffs in one direction. The
30 hanger *a* is fastened to the hat-rim just on the edge of the crown, as shown in Fig. II, and the spirals are so adjusted as to throw the muff inside the crown, as shown at *h*, Fig. II.
35 Fig. III illustrates how the points *c c* of the hanger are passed through the hat-rim *k*, and, being bent down, as shown, securely hold

the spiral in a proper position. *i*, Fig. II, shows the muff in position for covering the ear.

The casual observer will not notice that a hat is provided with this muff, as the hanger 40 can be made inconspicuous and the wire loop so slender that it will not only be out of sight, but the wearer of the hat will experience no inconvenience from it. When the wearer wishes to use the muffs, it is the work of a 45 moment to lift the hat, turn the muffs outward from inside the crown, holding them so until the hat is replaced on the head, when as soon as the hands are removed from them they will comfortably cover the ears. Simply 50 lifting the hat from the head causes the muffs to return to the inside of the hat. Thus the muffs are always ready, never in the way, and cannot be laid down and forgotten or left in a pocket "at home" or "at the office." 55

I do not wish to be limited in making the muff to the exact form as herein shown so long as I embody the principles of my invention.

What I claim, and desire to secure by Letters Patent, is—

An ear-muff comprising a wire frame, a covering therefor, and a hanger for securing said frame to a hat, the wire frame terminating in spirals wound around the shank of the hanger, 65 substantially as herein set forth.

Signed at Peekskill, county of Westchester, and State of New York.

HARVEY HADDEN.
